UNITED STATES PATENT OFFICE.

CARL G. TIDEMAN, OF WORCESTER, MASSACHUSETTS.

BELIEF MECHANISM FOR GEARING OF MACHINERY.

SPECIFICATION forming part of Letters Patent No. 752,267, dated February 16, 1904.

Application filed November 13, 1903. Serial No. 181,017. (No model.)

To all whom it may concern:

Be it known that I, **CARL G. TIDEMAN**, a citizen of the United States, residing at Worcester, in the county of Worcester and State of Massachusetts, have invented a new and useful Relief Mechanism for Gearing of Machinery, of which the following, together with the accompanying drawings, is a specification sufficiently full, clear, and exact to enable persons skilled in the art to which this invention appertains to make and use the same.

The object of my present invention is to provide an efficient means in connection with the gearing of wire-drawing blocks and other machinery for preventing sudden strains or shock upon the driven members and avoiding the jerking pull upon the wire when starting the machine into action.

My invention consists in mechanism constructed and organized for operation substantially as explained in the following description and illustrated in the accompanying drawings, wherein—

Figure 1 represents a side view, partly in section, of a relief mechanism embodying my invention. Fig. 2 represents a top plan view of the same; Fig. 3, a longitudinal vertical section of the resistance-cylinder and piston drawn to somewhat larger scale. Fig. 4 is a transverse section of the cylinder; Fig. 5, a back view of the piston-head, and Fig. 6 shows the arrangement of the relief mechanism in combination with the wire-drawing block and its driving-shafts.

35 As shown in the drawings, my improved mechanism comprises a wheel or gear A and a shaft B, upon which said wheel is mounted to turn loose or not keyed thereon. Either the gear A or the shaft B can be in its order 40 the driving element as in any instance desired; but for the purposes of this description it is assumed that the direction in which power and motion is transmitted is from the gear to the shaft, such being the arrangement most 45 conveniently applicable to wire-drawing machinery of the kind shown.

C indicates an armed hub, swing member, or cross-head arranged upon the shaft adjacent to the hub of the gear-wheel A and firmly keyed to the shaft by a spline *b* or other eff-

cient fastening, so that the cross-head, its arms 1 and 2, and shaft B will move together.

D indicates a resistance-cylinder pivotally connected with the gear-wheel in a manner that permits free oscillatory movement of the cylinder in relation to the wheel. As shown, a pintle or wrist-pin 3, formed on the bottom of the cylinder-body, extends through a bearing formed in the arm or plate of the gear-wheel and is secured in place by proper shoulders and a nut 4, arranged on the screw-threaded end of the pintle at the under side of the gear-wheel. The interior of the cylinder is provided with a piston-chamber 5, and a supplemental chamber 6 is combined therewith, a suitable by-pass 7 being provided from one chamber to the other adjacent to the cylinder-head. A piston F is fitted to move within the chamber 5 and is connected by a piston-rod I with the arm 1 of the cross-head C. Suitable packing devices are provided for the rod where it passes through the cylinder-head, and said head is tightly secured to the cylinder-body. The piston-disk is provided with one or more openings, holes, or ports 9 (preferably two) directly through it.

Within the interior of the cylinder I provide rigidly-projecting tapered pins or obstructing members 10 in corresponding alignment with the respective openings 9 and onto which said openings advance when the piston F is forced inward. The pins 10 can be threaded into the end of the cylinder-body or held therein by a nut on the threaded end of the pin or secured in any other efficient manner.

When in use, the piston-chamber 5 is filled with oil or other suitable liquid to afford resistance to the piston movement. The supplemental chamber 6 affords space for a moderate amount of air and space for receiving the oil when forced from the piston-chamber 5 by advance of the piston-rod thereinto.

The supplementary chamber 6 can be made of any convenient size and form and located at any convenient position in relation to the cylinder-body, the by-pass opening 7 thereby leading out from the piston-chamber 6 at a position back of the piston-disk when the latter is retracted. The taper or form of the 10

pin or obstructing member 10 can in any instance be made with more or less degree of taper or the taper varied so as to close the piston-ports 9 with greater or less quickness or at any particular point of its movement along the chamber 5.

G indicates a spring-resistance device, consisting of a segmental guard formed on or attached to the gear-wheel A and provided with an end abutment 8 and a support-way or circular cradle, preferably grooved along its inner face, with a spring or springs S disposed therein for exerting force against the arm 2 of the cross-head C in a direction for drawing the piston F toward the head of the cylinder and retaining the parts at normal idle position. In the present instance, as illustrated, the coiled-wire spring or springs S—one, two, or more of which can be employed—are arranged to act by their expansive force between the abutment 8 and arm 2, the guard being arranged for keeping said springs on the circular arc corresponding with the swing movement of the end of the arm 2, which is provided with a seat or bearing for the end of the spring or springs suitable for keeping the same in proper relation thereon as the movements are effected.

As applied to a wire-drawing block the gear-wheel with relief mechanism is arranged upon the upright shaft B, that carries upon its upper end the draft block or drum 15, which may be of usual or any suitable construction for pulling wire through the reducing-die at 16, which die and its support may be of the usual well-known construction. The gear-wheel A is driven by a gear or pinion H on the operating or power shaft P. The direction of the operative rotation is indicated by the arrow at 20 on Fig. 2. The clutch M for stopping and starting the mechanism may be arranged at any convenient position and operated by any suitable means.

In the operation when the clutch or power is thrown in for starting the mechanism the force of the power movement acts to carry forward the gear-wheel A, while the inertia of the driven members and strain of the wire from the die 16 acts as an opposing force through the shaft B and cross-head. The opposing force thus exerted tends to press the piston F inward against the body of oil in the piston-chamber 5 and to also compress the spring or springs S. As the oil can escape from the chamber only by flowing through the holes 9 in the piston, a resistance is afforded which, though slight at first, greatly increases in amount as the piston F moves toward the farther end of the chamber and the tapered pins 10 more and more obstruct or close the holes 9 in the piston, and thereby reduce the speed at which the oil can escape from in front of the piston. The compression of the springs S, which is simultaneously effected, also affords some additional

resistance. The effect produced by this mechanism is that instead of a quick inelastic start, as with ordinary gearing, and the instant jerking of the wire into full-speed movement the relief mechanism affords an easy elastic starting of the operated members and with a yielding effect proportional to the power required for bringing the operated members and wire draft without shock or extra strain from their inert condition up to the normal speed of movement. When the piston strikes the end of the cylinder, the power is transmitted by a positive unyielding advancement so long as the force is greater than the spring tension. When the clutch M or power is thrown off, the piston is caused to return to its primal position at the head of the cylinder by the expansive action of the spring or springs S, which causes the gear-wheel and cross-head arms to assume their original relation to each other.

While my invention is more especially designed for use in combination with wire-drawing machines, it may be employed in other machinery with equivalent effect, and I desire to include such use as within the scope of my claims.

I am aware that changes may be made in the construction of my relief mechanism by those skilled in the art without departing from the essential idea of means expressed in the claims. Therefore I do not wish to be limited to the special form of its embodiment herein shown.

What I claim, and desire to secure by Letters Patent, is—

1. A relief mechanism for gearing, comprising a wheel, a shaft whereon said wheel is loose mounted, a cross-head member mounted tight upon said shaft, an oil-resistance cylinder carried by said wheel, a piston within said cylinder and connected with said cross-head member, a spring arranged between the wheel and cross-head member and exerting tension for normally returning the parts to their primal position with the piston at the end of the cylinder.

2. A relief mechanism for gearing, comprising a shaft, a gear or wheel loose mounted thereon, a cross-head keyed to said shaft, a liquid-resistance cylinder pivotally attached to said gear-wheel, and having a piston-chamber and supplementary chamber, a piston-rod connected with said cross-head and carrying a piston having openings therethrough that works in said cylinder, tapered obstruction-pins fixed in said cylinder in alignment with the openings in the piston, and a reacting-spring for returning the piston to its primal position.

3. In a relief mechanism of the character described, the resistance-cylinder comprising a piston-chamber, and a supplementary chamber, with a by-pass uniting said chambers, tapered projecting pins within the piston-chamber; in combination with a piston provided

with openings in alinement with said pins and through which the said pins are projected as the piston advances, for the purpose set forth.

4. In a relief mechanism of the character described, the segmental spring-supporting guard having a spring-seating end abutment and a circular spring-supporting face along its inner curve; in combination with the wheel, the cross-head having an arm, an axial shaft for said wheel and cross-head, and a coiled-wire spring disposed between said abutment and cross-head arm within said guard.

5. The combination, of a shaft, a gear or wheel mounted loose thereon, a spring-resistance device carried on said wheel, an oil-re-

sistance device carried on said wheel, the pressure-piston for said oil-resistance provided with ports, an escapement-chamber at the back of the piston, means for increasing the closure of the piston-ports as the piston advances, and a cross-head carried and fixed on said shaft, and having arms that respectively engage with said oil-resistance piston and said spring-resistance spring, for the purposes set forth.

Witness my hand this 12th day of November, 1903.

CARL G. TIDEMAN.
